INVENTOR,
LARENCE C. SHIPP,

By Joseph A. Minutolo
Attorney.

UNITED STATES PATENT OFFICE.

CLARENCE C. SHIPP, OF INDIANAPOLIS, INDIANA.

AUTOMATIC FRESH-AIR-DAMPER CONTROL.

Application filed November 17, 1923. Serial No. 675,429.

To all whom it may concern:

Be it known that I, CLARENCE C. SHIPP, a citizen of the United States, residing at Indianapolis, in the county of Marion and State of Indiana, have invented a new and useful Automatic Fresh-Air-Damper Control, of which the following is a specification.

My invention relates to improvements in the control of the flow of fresh air to and through a heating radiator, and it is the purpose of my invention to regulate the amount of air admitted from the atmosphere without the building to the radiator by means entirely automatic, to meet the inside room requirements.

In the average home, and especially in public buildings, such as schools and hospitals, there is constant need of ventilation by an inflow of fresh air for the maintenance of efficiency, health, and comfort. The usual means of providing such ventilation generally requires close attention by one or more attendants in regulating the manual controls, and it frequently happens, as in a school room, other matters engaging the attention of the attendant, cause the attendant to overlook adjusting the fresh air control for a period of time until the room conditions have so changed as to have either an excess of cold air or to have too small an amount of fresh air being admitted.

It is the primary object of my invention to provide means whereby the fresh air requirements of a room are automatically provided for entirely independent of attendants and without expensive fans or blower equipment that necessitate installation of ducts and the like devices; and another equally important object of my invention is to house the automatic mechanism so it can not be tampered with and the time of opening and closing of the damper controlling the supply of outside air changed by unauthorized persons. This is particularly important in school rooms where children may tamper with an improperly change such an apparatus if left open to them. My invention provides a simple, effective, durable, and inexpensive installation that may be adapted to old as well as new buildings. I apply my invention to any of the well known steam, vapor, or hot water radiators.

I accomplish these and other objects as may hereinafter appear by the means as

shown in the accompanying drawing, in which—

Fig. 1 is a view in perspective of a radiator with fragments removed and with my automatic fresh air control in position; Fig. 60 2, a top plan view of the actuating bellows; and Fig. 3, a vertical section of the bellows taken on the line 3—3 of Fig. 2.

Like characters of reference indicate like parts throughout the several views. 65

In Fig. 1, the radiator comprised of the several sections 5, is enclosed on the back, front and ends by the shell or air diffuser 6. An upright pipe 7, extended upwardly along the radiator sections 5, and substantially to the top of the shell 6, is connected at its lower end to a coil of tubing 8, which in turn is connected to the head 9 of a bellows 10 that is comprised of a plurality of expandable chambers 34. The coil of tubing is provided to care for variations in assembly and to take up the vertical expansion of the walls of the pipe 7.

The head 9 is secured to the frame work 11, which frame work is supported by the shell 6. On the opposite end of the bellows 10, is the movable head 12, to which is attached the rod 13. Mounted on the rod 13 and bearing against the frame 11 and the head 12, is the compression spring 14 that tends to resist the expansive longitudinal movement of the bellows 10.

Pivots secured at one end to the arm 15 which forms a fulcrum extended from the frame 11, is the lever 16, to which is pivotally secured the rod 13 by means of a yoke end. To the other end of the lever 16, is pivoted a second lever 17 which extends backwardly from the radiator, and approximately at right angles to the lever 16, into a passage 18 leading through the building wall 19 to the outside atmosphere. A rocker arm 20, pivotally connected to the floor of the passage 18, pivotally engages the outer end of the link 17.

A connecting link 21 is pivoted at one end to the upper end of the rocker 20, and at its outer end to a damper 22, here shown in a closed position. The damper 22 may be opened outwardly about the hinge 23. 105 Protecting the air passage 18 are the storm louvres 24 and the screen 25.

On the inner side of the back of the shell 6 is mounted an indicating device to show from over the top of the radiator the open 110

or closed position of the damper 22. A chain 26 is connected to the link 17 at a point back of the rod 27 and passes under, outwardly, upwardly and around the bracket 28 and thence downwardly to the end of the rod 27 which rod is free to slide vertically through guides in the brackets 28 and 30. Adjustably secured to the rod 27 is the extension rod 31 that operates the indicating mechanism head 32 causing the words Open or Shut to appear in the window 33 as the upward or downward movement of the rod 31 may determine.

An expandible liquid is sealed within the connecting chambers formed by the pipe 7, coil 8, and bellows 10 and the relation of the expansion of the bellows 10 to the room temperature is such that when the room temperature is under that desired the bellows is in its normal contracted position as indicated in Fig. 1. As the room temperature increases, due to the heat from the radiator, the liquid expands in the pipe 7 causing in turn an increased pressure within the bellows 10, such that as the room temperature continues to rise, the bellows 10 will expand longitudinally, compress the spring 14, and push the rod 13 outwardly, causing the lever 16 to move its free end backwardly and in turn actuate the link 17, rocker 20, and link 21, such that the damper 22 is pushed open—the degree of opening depending upon further expansion of the confined liquid as may be occasioned by further increase in room temperature. As the link 17 moves backwardly, it pulls on the chain 26 so as to cause the rods 27 and 31 to rise and push the head 32 upward to bring the word Open in place within the window 33.

The bellows 10 is preferably enclosed in a housing 35, shown in Fig. 2 in fragments, but removed in Fig. 1 to show more clearly the bellows.

With the damper 22 now open, fresh air is rapidly drawn through the passage 18 up and around the heated radiator sections 5 and discharged into the room at a higher temperature than without. The air can only escape into the room from the top of the radiator as guided by the enclosing shell 6, such that disagreeable drafts are avoided. Should an excess of cold air be admitted, the room temperature will drop and cause a corresponding contraction of the fluid within the pipe 7, such that the bellows 10 will contract and the return spring 14 will extend and cause a reverse action of the mechanism intervening between the bellows 10 and the damper 22 to the effect that the damper 22 will close until the room temperature again rises, and more cold air is required. With the proper relation of the expansion of the fluid confined and the heat supplied by the radiator, the damper 22 will usually remain open to some degree

to supply a continuous flow of fresh air, although in extremely cold weather, the damper will intermittently open and close.

The expansion of the bellows 10 and the compression of the return spring 14 is preferably provided in my invention so that the damper 22 will start opening at a room temperature of $67\frac{1}{2}$ degrees Fahrenheit and will gradually continue opening until at $69\frac{1}{2}$ degrees the damper is wide open.

I have herein described my invention in the form now best known to me, but as it is obviously capable of many variations in structure as well as in range of temperature control without departing from the spirit of the invention, I do not desire to be limited to the precise form as shown any more than may be required by the following claims.

I claim:

1. In a device for controlling the flow of air through a heating radiator, the combination with a radiator, a radiator housing, an air passage discharging into the housing, and a damper in the passage, of a vertical fluid containing member within the radiator housing containing a fluid having a high coefficient of expansion, a horizontal expanding member located in the housing and communicating with the vertical fluid containing member, and means actuated by the expansion and contraction of the horizontal member for opening and closing the damper.

2. In a device for controlling the flow of air through a heating radiator, the combination with a radiator, a radiator housing, an air passage discharging into the housing, and a damper in the passage, of a vertical fluid containing member within the housing containing a fluid having a high coefficient of expansion and extending substantially from the bottom to the top of the radiator housing; a horizontal expanding member located in the housing and communicating with the vertical fluid containing member through a flexible connection; and means actuated by the expansion and contraction of the horizontal expanding member for opening and closing the damper.

3. In a device for controlling the flow of air through a heating radiator, the combination with the radiator, a radiator housing, an air passage discharging into the housing, and a damper in the passage, of a vertical fluid containing member within the housing containing a fluid having a high coefficient of expansion and extending substantially from the bottom to the top of the radiator housing; a horizontal expanding member located in the housing and communicating with the vertical fluid containing member through a flexible connection, said horizontal expanding member consisting of a plurality of inter-communicating expandible chambers having a non-expandible head at

one end fixed to a frame supported by the radiator housing and a movable non-expansible head at the opposite end and having a rod connecting with said movable head and passing through said frame; and means actuated by the expansion and contraction of the said horizontal member for opening and closing the damper.

4. In a device for the controlling of the flow of air through a heating radiator, the combination with the radiator, a radiator housing, an air passage discharging into the housing, and a damper in the passage, of a vertical fluid containing member within the housing containing a fluid having a high coefficient of expansion and extending substantially from the bottom to the top of the radiator housing; a horizontal expanding member located in the housing and communicating with the vertical fluid containing member through a flexible connection, said horizontal expanding member consisting of a plurality of inter-communicating expansible chambers between non-expansible heads, one of said heads being free to move; means of resisting such movement; and means actuated by the expansion and contraction of the horizontal member for opening and closing the damper.

5. In a device for controlling the flow of air through a heating radiator, the combination with the radiator, a radiator housing, an air passage discharging into the housing, and a damper in the passage, of a vertical fluid containing member within the housing extending substantially from the bottom to the top of the radiator housing and containing a fluid of a high coefficient of expansion; a horizontal expanding member within the housing and communicating with the vertical fluid containing member through flexible tubing, said horizontal expanding member being comprised of a fixed non-expansible head, a plurality of intercommunicating expansible chambers between the fixed head and a movable non-expansible head, and a rod extending from the movable head, all supported by a frame, a spring resisting the expansion and aiding the contraction of the horizontal expanding member; a lever fulcrumed on the frame of the horizontal ex-

panding member and operated by the rod extending from the movable head; a rocker arm pivoted to a wall of the air passage; a connecting link pivoted to the rocker arm and the damper; and a connecting lever pivoted to the rocker arm and the lever fulcrumed on the frame of the expanding member.

6. In a device for controlling the flow of air through a heating radiator, the combination with the radiator, a radiator housing, an air passage discharging into the housing, and a damper in the passage, of a vertical fluid containing member within the radiator housing, containing a fluid having a high coefficient of expansion, a horizontal expanding member located in the housing and communicating with the vertical fluid containing member, means actuated by the expansion and contraction of the horizontal member for opening and closing the damper, and means of indicating the position of the damper from the travel of said expanding member.

7. In a device for controlling the flow of air through a heating radiator, the combination with the radiator, a radiator housing, an air passage discharging into the housing, and a damper in the passage, of a fluid containing member located in the housing and containing a fluid having a high coefficient of expansion, an expanding member, and means actuated by the expansion and contraction of the expanding member for opening and closing the damper.

8. In a device for controlling the flow of air through a heating radiator, the combination with the radiator, a radiator housing, an air passage discharging into the housing, and a damper in the passage, of a fluid containing member containing a fluid having a high coefficient of expansion, an expanding member, and means actuated by the expansion and contraction of the expanding member for opening and closing the damper, the fluid containing member and the expanding member both being located within the housing.

Signed at Indianapolis, Indiana, this the 100
15th day of November, 1923.

CLARENCE C. SHIPP.
